UNITED STATES PATENT OFFICE.

EDWARD J. McGUIRK, OF NEWARK, NEW JERSEY, ASSIGNOR TO GREENE, TWEED & CO., A CORPORATION OF NEW YORK.

DESIGN FOR AN ASH TRAY.

Application filed March 16, 1927. Serial No. 21,156. Term of patent 14 years.

To all whom it may concern:

Be it known that I, EDWARD J. McGUIRK, a citizen of the United States, and a resident of Newark, in the county of Essex and State of New Jersey, have invented a new, original, and ornamental Design for Ash Trays, of which the following is a specification, reference being had to the accompanying drawing, forming part thereof.

Figure 1 is a front elevation of an ash tray showing my new design; Figure 2 is a side elevation thereof, and Figure 3 is a top plan view thereof.

I claim:

The ornamental design for an ash tray, as shown.

EDWARD J. McGUIRK.
